UNITED STATES PATENT OFFICE.

JAMES P. CUNNINGHAM, OF CINCINNATI, OHIO, ASSIGNOR TO WALTER R. GRISSEL,
OF CEDAR RAPIDS, IOWA.

AUTOMATIC ROLLER-BEARING FOR WINDOW-SASHES.

1,127,196.

Specification of Letters Patent.

Patented Feb. 2, 1915.

Application filed May 19, 1914. Serial No. 839,609.

To all whom it may concern:

Be it known that I, JAMES P. CUNNINGHAM, citizen of the United States, residing at Cincinnati, in the county of Hamilton and State of Ohio, have invented certain new and useful Improvements in Automatic Roller-Bearings for Window-Sashes, of which the following is a specification.

My invention relates to windows, and particularly to sash supporting means therefor.

One object of my invention is the provision in connection with window sashes of bearing rollers disposed on the side edges of the sashes and means preferably connected to the sash weights for exerting a constant outward pressure on the rollers to automatically force the rollers against the inner face of the window casing, thus preventing the window sashes from rattling, providing a firm support for the window sashes in their travel and causing sufficient engagement between the window sashes and the casing to prevent the windows being drawn too easily upward by the weights.

Other objects will appear in the course of the following description.

My invention is illustrated in the accompanying drawings, wherein:

Figure 1 is a front view of a window constructed in accordance with my invention. Fig. 2 is a front elevation of the sash, a portion of the jamb and the tensioning device mounted therein. Fig. 3 is an edge view of the sash with the tensioning device mounted therein. Fig. 4 is a perspective view of one of the rollers and the yoke supporting it.

Referring to these drawings it will be seen that the frame of my improved window comprises the oppositely disposed hollow metallic jambs 2, the hollow metallic lintel 3, and the sill 3^a. The inner wall of the jamb is so formed as to provide a middle parting strip and sash channels on each side of the parting strip, each channel being formed with a longitudinally extending guiding corrugation or rail 17 which is braced by a corrugated strip of metal 19.

The upper and lower sashes are designated A and B and both are formed in the same manner. Each sash includes the laterally disposed hollow sheet metal sash bars 33 housing rollers 37. There are two of

these rollers for each side bar of each sash frame.

Each roller 37 is mounted in a yoke designated generally 41. This yoke is composed of sheet metal bent to provide the spaced side walls 42, these side walls being connected for a portion of the length of the yoke by the web 43, leaving an open space between the side walls and behind said web, as at 44. Each roller 37 is channeled upon its periphery and is mounted upon an arbor 45, mounted in the side walls 42.

Passing through the side walls of the yoke and in the space 44 is a pivot pin 46 and surrounding this pivot pin and rotatably mounted thereon between the side walls 42 is a sleeve 47. This pivot pin 46 extends through the side walls of the bar 33. There are two yokes disposed reversely to each other so that the rollers are disposed at the adjacent ends of the yoke. These rollers may be disposed in any desired relation to each other. Disposed at the lower end of each hollow side bar 33 of the sash frame is a transverse pin 48 to which is clamped one end of a tension member 49. As illustrated, this tension member is in the form of a steel strip relatively narrow in width which passes up over the front or outside portion of the roller 47 of the lowest yoke and then up back of the web 43 of said lowest yoke. The tension strip is carried upward behind the web of the upper yoke and upward and outward in front of the sleeve of the uppermost pivot pin 46 then upward between pins 50 carrying upon them sleeves 51 and the upper end of this flexible tape or tension member 49, as illustrated in Fig. 1 is connected to the sash tape 32^a by means of a clip 52 of any suitable construction. These sash tapes 32^a in turn are connected to the sash-weights 32. The pivot pins 46, 48 and the pins 50 each consist of sections of steel tubing attached at each end to receive flat headed tap screws with a shoulder to prevent the displacement of the pins and preferably the sides 42 of the yokes are braced at their lower ends by means of a transverse bracing web 43^a.

It will be seen from Fig. 2 that the tension member 49 is deflected out of a straight line by passing behind the free ends of the yokes 41 and then being carried forward

above and below the yokes over the pivot pins thereof. As a consequence when strain is placed upon this tension member it will force the tension member to straighten out 5 which will force the free ends of the yokes and therefore force the rollers 37 outward and into contact with the tracks. Thus, when the counter weights are detached from the sash frame there is no outward force exerted upon the rollers 37 but when the 10 weights are attached this outwardly acting force exerted upon these rollers will be in proportion to the size of the counter-weight. It will be seen that with a construction as 15 heretofore described that the window sashes are positively guided in their movements and held from any rattling by the engagement of the rollers 37 with the tracks 17. A sufficient pressure is exerted at all times upon 20 these rollers to hold the window sash in its proper position and the outward force exerted upon the rollers causes them to press against the tracks with sufficient force to resist the action of the counter-weight to 25 some extent but permit the easy movement of the window sashes.

Having thus described the invention what is claimed as new is:—

1. In a window, a jamb and a sash, a bearing member mounted on the sash for outward movement against the jamb, a sash weight, and means connected to the sash weight for forcing said bearing member outward against the jamb.

35 2. In a window, a jamb, a sash, a bearing roller, a roller supporting member pivotally connected to the sash to permit the roller to move outward against the jamb, a sash weight, and means operatively connected to the sash weight for forcing said roller outward.

3. In a window, a jamb, a sash, a bearing roller carried by the sash, a yoke pivoted at one end to the sash and at its other supporting said bearing roller, a weight, a flexible tension element distorted from a straight line by said roller supporting member connected at one end to the sash and at its other end operatively connected to the weight, the 45 tension on said element acting to force it to a straight line and thereby forcing said roller outward.

4. In a window, a jamb, a window sash coacting with the jamb and having a vertically disposed recess in its side edge, upper and lower supporting members each disposed in said recess and pivoted to the walls thereof, each at one end, bearing rollers carried by said supporting members, a counter weight 55 in the jamb, and a flexible tension element forming connecting means between the sash and counterweight and distorted from a straight line by said roller supporting mem-

bers, whereby the said weight shall act to force the tension element into a straight line, 65 thereby forcing said rollers outward.

5. In a window, a jamb, a sash coacting therewith and having a recess in its side edge extending longitudinally thereof, upper and lower roller supporting members, the adjacent ends of said members each supporting a bearing roller, pivot pins passing through the outer ends of said roller supporting members, a counter-weight disposed in the jamb, and a flexible tape forming connecting means 75 between the sash and counter-weight and passing in front of both of said pivot pins and behind the free ends of said supporting members and being thereby deflected from a straight line.

6. In a window, a jamb, a sash coacting therewith, a sash counter-weight disposed in the jamb, a roller supporting member disposed in a recess in the side edge of the sash, said roller supporting member comprising a 85 yoke having spaced sides, and a cross bar at one end connecting said sides, a roller supported between said sides adjacent said cross bar, a pivot pin passing through the other ends of the sides, and supported in the sash, 90 and a flexible tape forming connecting means between the sash and counter-weight and passing behind the cross bar on the free end of the yoke and passing between said side members and over the outer face of the pivot 95 pin.

7. In a window, a jamb having a longitudinally extending track formed upon its face, a sash coacting with the jamb and longitudinally recessed upon its side edge, a 100 counter-weight, upper and lower pivot pins passing through said recess, sleeves surrounding said pivot pins, upper and lower yokes disposed in said recess, each of said yokes comprising a cross bar and spaced 105 sides and mounted upon a pivot pin passing through said sides, a roller for each yoke mounted adjacent the cross bar thereof and upon the free end of the yoke, said roller being grooved to engage the track, a flexible 110 tape forming connecting means between the sash and counter-weight and passing upward over the pivot pin of the lowest yoke then behind the cross bar thereof, upward along the recess and behind the crossbar of the upper yoke, then forward in front of the pivot pin of the upper yoke, and guiding pins 115 above the upper yoke between which the tape passes.

In testimony whereof I affix my signature 120 in presence of two witnesses.
